UNITED STATES PATENT OFFICE

2,066,460

APPARATUS FOR MAKING CIGARETTES

William Frederick Maitland Edwards, London,
England, assignor to Filter Tips Limited, Lon-
don, England, a British company

Application November 7, 1934, Serial No. 751,951
In Great Britain November 9, 1933

22 Claims. (Cl. 131—43)

This invention relates to cigarettes and is par-
ticularly concerned with the production of filter
tip or like composite cigarettes by a method
wherein spaces are formed in the continuous
5 tobacco filling for the reception of filter tips or
other insertions.

The present invention has among its objects
to provide improvements in such method of pro-
duction and, further, to provide improved, simple
10 and effective apparatus for carrying out the im-
proved method.

According to the present invention, a continuous
tobacco filling is cut at spaced positions while
closely confined and/or under compression to en-
sure clean-cut ends, and spaces for the reception
15 of filter tips or other insertions are formed by
the lateral removal of subdivided parts of the
filling.

For carrying out the method, apparatus may be
20 provided comprising a rotatable wheel or drum
having a circumferential groove or channel in
its periphery into which groove or channel the
tobacco filling is guided and held or confined dur-
ing its passage to a position at which it is deliv-
25 ered from the groove or channel on to a con-
tinuous paper strip, and cutting and tobacco-remov-
ing means associated with the wheel or drum
and operating on the tobacco filling in the cir-
cumferential groove or channel through trans-
30 verse slots or the equivalent. Means for applying
lengths of filter tip or other insertion ma-
terial may be associated with the means for re-
moving the subdivided parts of the tobacco fill-
ing. The tobacco filling may be fed into the cir-
35 cumferential groove or channel by means of a
compression wheel or wheels cooperating with a
guide tube and serving to compact the continuous
rod of tobacco as it is delivered from the
forming belt into the said guide tube. The paper
40 strip, after receiving the lengths of filling from
the circumferential groove or channel in the
wheel or drum, passes into a garniture arranged
in close proximity to the point at which the paper
strip leaves the wheel or drum and by which it
45 is formed into a continuous paper tube which is
subsequently cut off into lengths to provide ci-
garettes having insertions at the mouthpiece ends
or at intermediate positions in the length there-
of, or, if no insertion material is applied, to
50 provide cigarettes having hollow mouthpieces
into which filter tips or other insertions may be
applied subsequently. The tobacco-cutting and
removing means associated with each of the
transverse slots of the wheel or drum may com-
55 prise a blade mounted on the wheel or drum by
the provision of an oscillatable arm or the equiva-
lent, side walls connected to the blade and pro-
vided with inclined cutting edges for severing the
tobacco filling, and a transverse wall forming
60 with the blade and with the side walls a scoop

for effecting the lateral removal of the severed
portion of the tobacco filling. A chamber may
be provided behind the transverse wall for the
reception of a filter tip or mouthpiece insertion
which is thereby carried into alignment with the
5 circumferential groove or channel when the se-
vered portion of the tobacco filling is removed.
The filter tip or mouthpiece insertion may be
retained in the chamber by suction or other
means up to the point at which it is to be de-
10 posited on the paper strip. The tobacco removed
by the scoops may be carried away by means of
a suction nozzle.

The invention is hereinafter described by way
of example with reference to the accompanying
diagrammatic drawing, in which:—

Figure 1 is a side elevation illustrating one
construction of apparatus in accordance with the
invention;

Figure 2 is a section on the line II—II, Fig-
ure 1; and

Figure 3 is a view similar to Figure 2 showing
the tobacco-cutting and removing means in the
position occupied prior to the cutting and remov-
ing operation.

Figure 4 is a fragmentary perspective view of
the wheel of the apparatus according to the pres-
ent invention.

In carrying the invention into effect according
to one embodiment and with reference to the 30
accompanying diagrammatic drawing, the con-
tinuous tobacco filling 1 carried from the feed
hopper (not shown) on a belt 2 cooperating with
a guide 2a is fed by means of compression wheels
3, 4 into a guide tube 5 by which the filling is 35
delivered into a circumferential groove or chan-
nel 6a in a segmental rim of a wheel 6. The to-
bacco filling is retained in the circumferential
groove or channel by means of a fixed guide 7
up to the point at which it is delivered on to the 40
continuous paper strip 9 which may be carried
by a wrapping belt 8, both the belt and the pa-
per strip conveniently passing around the same
roller 10 and being led into the garniture 11.

Associated with each of the transverse slots 45
formed between the segmental parts of the rim
of the wheel 6 is a tobacco-cutting and removing
device. In one construction an arm 12 is pivoted
on a hollow pin 13 mounted in a slotted part 6b
of the wheel 6, the outer end of the arm 12 being 50
formed with a groove or channel 12a which, in
the position shown in Figure 2, coincides with
the circumferential groove or channel 6a. The
outer end of the arm 12 also is provided with a
laterally extending blade 12b which is adapted 55
to enter between the tobacco filling 1 and the
guide 7, and also with side walls 12c formed with
inclined cutting edges whereby the tobacco fill-
ing 1 is sub-divided as the arm 12 is moved into
the position shown in Figure 2, the blade 12b and 60

the side walls 12c in conjunction with a transverse wall at the rear thereof forming a scoop by which the severed portion of the tobacco filling is removed, as shown in Figure 2.

5 The arm 12 may be operated by the provision of a roller 12e co-operating with a cam ring 14 supported by arms or brackets 15, 16, the arm 12 being normally held outwards by means of a spring 12d connected to an arm 6c fixed to the 10 wheel 6 and being pressed inward as it approaches the position at which the paper strip 9 engages the wheel 6 by means of the parts 14a of the cam ring 14.

Filter tips 20 or other desired insertions may 15 be fed from forming mechanism 17 or a transfer drum, hopper or the like by means of a plunger 18 and directed through a spoon or guide 17a into the chambers formed by the grooves or channels in the outer ends of the arms 12. In order 20 to hold each filter tip in the respective groove or channel 12a during its passage to the point at which it is deposited on the paper strip 9, a passage 12f in the arm communicates at the lower end with the groove or channel 12a and at the 25 upper end through an opening 13a with the hollow pin 13 which in turn communicates with the passage 6d which, from the point of application of the filter tips or the like to the point of deposition thereof, is in communication with a bore 19a in a fixed spindle 19 carrying the wheel 6 through a slot 19b, such bore being connected to a suction pipe. This construction operates to cut off the suction after passage 6d passes slot 19b in element 19.

30 It will be understood that the filter tips 20 or the like are fed into the grooves or channels 12a when the arms 12 are in the position shown in Figure 3. Alternatively, the cam ring 14 may be formed so that the arms 12 move into the position 35 shown in Figure 2 to receive the filter tip 20 or the like from the spoon or guide 17a. When the arms 12 are operated by the part 14a of the cam ring so as to be moved into the position shown in Figure 2 part of the tobacco filling is severed 40 and removed and the filter tip 20 or the like is brought into position in the space so formed. The tobacco carried out by the scoop may be removed by the provision of a suction nozzle 21 or other suitable means.

45 50 The composite filling consisting of alternate lengths of tobacco and filter tips or the like is carried away on the paper strip 9 from the wheel 6 to the garniture 11 or equivalent means whereby the paper strip is wrapped around the continuous filling to provide a rod which is subsequently cut off at the desired positions to produce cigarettes each containing a length of tobacco and a filter tip or other mouthpiece or intermediate insertion.

55 It will be appreciated that, inasmuch as the 60 cutting and other devices acting on the tobacco rod are carried by the wheel or drum and move therewith, the flow of the continuous tobacco rod is uninterrupted throughout the operations hereinbefore described, while, owing to the fact that it is closely confined and/or compressed during 65 the cutting operation, clean-cut ends to the severed parts of the tobacco are ensured. If desired, the blade 12b may have its inner face arranged at a substantial inclination so as to apply increased compression to the tobacco filling prior 70 to or during the cutting thereof.

75 If desired, the means for applying filter tips or the like in the spaces formed in the continuous tobacco filling may be omitted so that when the continuous paper tube is cut off into lengths ciga-

rettes may be provided having hollow mouthpieces which, if desired, may have filter tips or the like subsequently inserted therewith.

The invention is applicable to the production of cigarettes having any desired mouthpiece or other insertion. For instance, the invention may be applied to the production of cigarettes provided with filter tips formed from crepe paper with or without intervening layers of filtering or like material. If desired, the insertions may be 10 in the form of wads or tufts of cotton wool or similar material or may consist wholly or in part of tobacco, in which latter case cigarettes containing tobacco of two different kinds or characteristics may be readily produced.

15 It will be understood that the invention is not limited to the particular embodiment hereinbefore described. For instance, the continuous tobacco filling may be carried to the wheel or drum and confined in the circumferential groove 20 or channel therein by the paper strip itself and/or by an endless belt. Furthermore, if desired, the means for applying the filter tips or other insertions into the spaces formed in the tobacco filling may be separate from or operated independently 25 of or in conjunction with the tobacco-cutting and removing means.

What I claim is:—

1. An apparatus of the character described, comprising a rotatable member having transverse slots and a circumferential channel in its periphery into which channel the tobacco filling is guided and held during its passage to a position at which it is delivered from the channel on to a continuous paper strip, and cutting and 30 tobacco-removing means associated with the rotatable member and operating on the tobacco filling in the circumferential channel through said transverse slots.

2. An apparatus of the character described, 40 comprising a rotatable member having a circumferential channel in its periphery, means for introducing a tobacco filling into said channel, means for retaining said filling in said channel during a portion of a revolution of said member, 45 and means carried by said rotatable member for cutting and removing a section of said filling from said channel.

3. An apparatus of the character described, 50 comprising a rotatable member having a circumferential channel in its periphery, means for introducing a tobacco filling into said channel, means for retaining said filling in said channel during a portion of a revolution of said member, 55 means carried by said rotatable member for cutting and removing a section of said filling from said channel, and means associated with said cutting means for positioning an insertion in the space provided by removal of said section of the filling.

4. An apparatus of the character described, comprising a rotatable member having a circumferential channel in its periphery, means for introducing a tobacco filling into said channel, means for retaining said filling in said channel 65 during a portion of a revolution of said member, means carried by said rotatable member for cutting and removing a section of said filling from said channel, and means carried by said cutting means for positioning an insertion in the space 70 provided by removal of said section of the filling.

5. An apparatus of the character described, comprising a rotatable member having a circumferential channel in its periphery, and a radially extending slot, means for introducing a tobacco 75

- filling in said channel, and means carried by said rotatable member and movable in said slot for cutting and removing a section of the filling in said channel.
6. An apparatus of the character described, comprising a rotatable member having a circumferential channel in its periphery, and a radially extending slot, means for introducing a tobacco filling in said channel, means carried by said rotatable member and movable in said slot for cutting and removing a section of the filling in said channel, and means carried by said cutting means for positioning an insertion in the space provided by removal of said section of the filling.
7. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, and means carried by said cylindrical member and movable through said slots for severing and removing sections of the filling between said segments.
8. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, means carried by said cylindrical member and movable through said slots for severing and removing sections of filling between said segments, and means for retaining said filling in said channel during travel of said cylindrical member from the filling introducing means to said wrapper strip.
9. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, means carried by said cylindrical member and movable through said slots for severing and removing sections of filling between said segments, and means associated with said severing means for positioning an insertion in the spaces provided by the removal of sections of the filling.
10. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, an arm mounted in each of said slots to swing about an axis perpendicular to the axis of rotation of said cylindrical member, a pair of blades carried by the free end of said arm, and means for swinging said arm to sever a section of the filling in said channel.
11. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, an arm mounted in each of said slots to swing about an axis perpendicular to the axis of rotation of said cylindrical member, means carried by the free end of said arm for severing a section of said filling, and means for swinging said arm to effect the severing operation.
12. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, an arm mounted in each of said slots to swing about an axis perpendicular to the axis of rotation of said cylindrical member, means carried by the free end of said arm for severing a section of said filling, and means for swinging said arm to effect the severing operation.
13. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, an arm mounted in each of said slots to swing about an axis perpendicular to the axis of rotation of said cylindrical member, means carried by the free end of said arm for severing a section of said filling, means on the free end of said arm for receiving an insertion, and means for swinging said arm to sever a section of filling and deposit the insertion carried by the arm in the space provided by removal of the severed section of the filling.
14. An apparatus of the character described, comprising a rotatable cylindrical member divided by radially extending slots into a plurality of circumferentially spaced segments, said cylindrical member having a circumferential channel in the periphery thereof, means for introducing a cigarette filling in said channel, means for moving a strip of cigarette wrapper tangentially relative to said cylindrical member to receive the cigarette filling from said channel, an arm mounted in each of said slots to swing about an axis perpendicular to the axis of rotation of said cylindrical member, a blade carried at the end of said arm, side walls connected to the blade and provided with inclined cutting edges for severing the cigarette filling.

severing the filling, and a transverse wall forming with the blade and with the side walls a scoop for effecting the lateral removal of the severed portion of the filling.

- 5 15. An apparatus of the character described, comprising a rotatable cylindrical member divided by radially extending slots into a plurality of circumferentially spaced segments, said cylindrical member having a circumferential channel 10 in the periphery thereof, means for introducing a cigarette filling in said channel, means for moving a strip of cigarette wrapper tangentially relative to said cylindrical member to receive the cigarette filling from said channel, an arm mounted 15 in each of said slots to swing about an axis perpendicular to the axis of rotation of said cylindrical member, a blade carried at the end of said arm, side walls connected to the blade and provided with inclined cutting edges for severing the filling, 20 a transverse wall forming with the blade and with the side walls a scoop for effecting the lateral removal of the severed portion of the filling, and a chamber provided behind said transverse wall for the reception of an insertion to be positioned in 25 place of the section of the filling removed.
16. An apparatus of the character described, comprising a rotatable cylindrical member divided by radially extending slots into a plurality of circumferentially spaced segments, said cylindrical member having a circumferential channel 30 in the periphery thereof, means for introducing a cigarette filling in said channel, means for moving a strip of cigarette wrapper tangentially relative to said cylindrical member to receive the cigarette filling from said channel, an arm mounted in each of said slots to swing about an axis perpendicular to the axis of rotation of said cylindrical member, a blade carried at the end of said arm, side walls connected to the 35 blade and provided with inclined cutting edges for severing the filling, a transverse wall forming with the blade and with the side walls a scoop for effecting the lateral removal of the severed portion of the filling, a chamber provided behind 40 said transverse wall for the reception of an insertion to be positioned in place of the section of the filling removed, and suction means for retaining said insertion in said chamber.

17. An apparatus of the character described, 50 comprising a hub, a plurality of spokes extending radially from said hub, a plurality of circumferentially spaced segments carried by said spokes to provide a radially slotted rim, said rim having a circumferential channel in the periphery thereof, means for introducing a cigarette filling into said channel, means for supporting a paper strip in association with said rim to receive said filling, and means operable during travel of said rim and filling, from the filling introducing means to the 55 paper strip, for severing and removing a section of said filling.

18. An apparatus of the character described, comprising a hub, a plurality of spokes extending radially from said hub, a plurality of circumferentially spaced segments carried by said spokes to provide a radially slotted rim, said rim having a circumferential channel in the periphery thereof, means for introducing a cigarette filling into said channel, means for supporting a paper strip 60 in association with said rim to receive said filling, means operable during the travel of said rim and filling, from the filling introducing means to the paper strip, for severing and removing a section of said filling, and means associated with the severing means for positioning an insertion in the 65

space provided by removal of said severed section of the filling.

19. An apparatus of the character described, comprising a hub, a plurality of spokes extending radially from said hub, a plurality of circumferentially spaced segments carried by said spokes to provide a radially slotted rim, said rim having a circumferential channel in the periphery thereof, means for introducing a cigarette filling into said channel, means for supporting a paper strip in association with said rim to receive said filling, means carried by the spokes for supporting an arm to swing between said segments, and means carried by the free end of said arm for severing and removing a section of said filling.

20. An apparatus of the character described, comprising a hub, a plurality of spokes extending radially from said hub, a plurality of circumferentially spaced segments carried by said spokes to 20 provide a radially slotted rim, said rim having a circumferential channel in the periphery thereof, means for introducing a cigarette filling into said channel, means for supporting a paper strip in association with said rim to receive said filling, 25 means carried by the spokes for supporting an arm to swing between said segments, means carried by the free end of said arm for severing and removing a section of said filling, and a chamber on the end of said arm for receiving an insertion 30 to be positioned in place of the removed section of the filling.

21. An apparatus of the character described, comprising a hub, a plurality of spokes extending radially from said hub, a plurality of circumferentially spaced segments carried by said spokes to provide a radially slotted rim, said rim having a circumferential channel in the periphery thereof, means for introducing a cigarette filling into said channel, means for supporting a paper strip 35 in association with said rim to receive said filling, means carried by the spokes for supporting an arm to swing between said segments, means carried by the free end of said arm for severing and removing a section of said filling, a chamber 40 on the end of said arm for receiving an insertion to be positioned in place of the removed section of the filling, and suction conduits provided in said arms, spokes and hub for placing said chamber in communication with a source of suction to 45 retain the insertions in said chamber.

22. An apparatus of the character described, comprising a hub, a plurality of spokes extending radially from said hub, a plurality of circumferentially spaced segments carried by said spokes 55 to provide a radially slotted rim, said rim having a circumferential channel in the periphery thereof, means for introducing a cigarette filling into said channel, means for supporting a paper strip in association with said rim to receive said filling, 60 means carried by the spokes for supporting an arm to swing between said segments, means carried by the free end of said arm for severing and removing a section of said filling, a chamber on the end of said arm for receiving an insertion to 65 be positioned in place of the removed section of the filling, suction conduits provided in said arms, spokes and hub for placing said chamber in communication with a source of suction to retain the insertions in said chamber, and means for controlling the application and cessation of suction to said chamber.
